LADY'S STOCKING

George J. Apar, Long Island City, N. Y.

Application December 26, 1951, Serial No. 17,835

Term of patent 3½ years

(Cl. D47—7)

To all whom it may concern:

Be it known that I, George J. Apar, a citizen of the United States, residing at Long Island City, in the county of Queens and State of New York, have invented a new, original, and ornamental Design for a Lady's Stocking, of which the following is a specification, reference being had to the accompanying drawing, forming part thereof.

Fig. 1 is a side perspective view of a lady's stocking showing my new design, and

Fig. 2 is an enlarged fragmentary view of the stocking shown in Fig. 1 illustrating the decoration in detail.

The opposite side of the stocking (not shown in the drawing) is conventionally plain.

I claim:

The ornamental design for a lady's stocking, as shown and described.
